UNITED STATES PATENT OFFICE.

JOSEPH MRAZEK, OF ASTORIA, NEW YORK.

DESIGN FOR A COVER FOR A DISH OR SIMILAR ARTICLE.

Application filed June 8, 1926. Serial No. 17,977. Term of patent 7 years.

To all whom it may concern:

Be it known that I, JOSEPH MRAZEK, a citizen of the United States of America, residing at Astoria, Long Island, in the county of Queens, State of New York, have invented a new, original, and ornamental Design for Cover for a Dish or Similar Article, of which the following is a specification, reference being had to the accompanying drawing, forming a part thereof.

In the drawing, Figure 1 is a plan view of the article, showing my new design.

Fig. 2 is an edge view thereof.

I claim:

The ornamental design for a cover for a dish or similar article substantially as shown.

JOSEPH MRAZEK.
